UNITED STATES PATENT OFFICE.

THOMAS FARMER, JR., OF ALBANY, NEW YORK, ASSIGNEE TO CONSOLIDATED CAR HEATING COMPANY, OF ALBANY, NEW YORK, A CORPORATION OF WEST VIRGINIA.

ELECTROMAGNETIC CONTROL OF PNEUMATIC DOOR-MOTORS.

1,075,704.

Specification of Letters Patent. Patented Oct. 14, 1913.

Application filed June 1, 1912. Serial No. 700,981.

To all whom it may concern:

Be it known that I, THOMAS FARMER, JR., a citizen of the United States, residing at Albany, county of Albany, State of New York, have invented certain new and useful Improvements in Electromagnetic Control of Pneumatic Door-Motors, the following being a full, clear, and exact disclosure of the one form of my invention which I at present deem preferable.

For a detailed description of the present form of my invention, reference may be had to the following specification and to the accompanying drawings, which illustrate my invention, wherein—

Figure 1 illustrates my invention diagrammatically; Fig. 2 is an enlarged section of the valve.

My invention relates to the control of a reciprocating pneumatic door motor in such a way that the door may be either opened or closed and in either condition the motor may be left for an indefinite period with the air pressure on and the electric circuit closed, while by breaking the electric circuit the motor will be left in a neutral condition with air pressure balanced so that the door can be moved by hand. By this means also the door can be advanced in either direction step by step. In my arrangement I provide a double acting cylinder motor, each end of which is provided with a separate spring-closed valve which merely admits air to the cylinder or, on the other hand, exhausts the cylinder to the atmosphere. For each separate valve I provide an individual electromagnet, of special construction to enable it to remain indefinitely on closed-circuit and the switch-control of these magnets is such that, when the circuit of a magnet is closed, the valve will be opened against the force of its closing spring in a position to admit air to its corresponding cylinder. Thus the circuit is always closed through one magnet or the other except at the particular instants when the door is started toward the opposite end of its route, or stopped in its travel and left neutral.

Referring to the drawing, A represents a pneumatic door motor of a kind now well known in practice and its construction, which forms no part of my invention, will

be found in detail in the patent of Mr. McElroy No. 1,002,596, dated September 5, 1911.

55

In brief, 1 represents a separator cylinder for opening the door and 2 a similar separate cylinder for closing it. The door is indicated at D and is connected by link 4 to a crosshead 5, which slides on the outside 60 of cylinder 1 and is connected (by rod 7 which passes through a guide 8) to a similar crosshead 6 which slides on the outside of cylinder 2. These connected crossheads and the door are moved from left to right (to 65 close the door) by the admission of air pressure to the left hand end of cylinder 2 and are moved from right to left (to open the door) by the admission of air pressure to the right hand end of cylinder 1, the in- 70 active cylinder during each movement being open to the atmosphere through the same pipe that admits pressure thereto when it is the active cylinder. A dash-pot cylinder 10 serves to deaden the door-closing movement 75 and a similar cylinder 9 serves to deaden the door-opening movement.

B¹ represents the control valve for cylinder 1, and B² represents a similar valve (shown in section) for cylinder 2. The 80 casting 20 has a recess 28 at its top which communicates with the atmosphere through exhaust duct 27 and also a control chamber 23 which communicates with the pipe 12 leading to the rear, left hand end of cylinder 2. It also contains a lower recess 24 closed by a perforated nut 21 through which the air enters from supply pipe 13 by way of the branch 14. The top and bottom recesses 85 both communicate with the control chamber 23 by a vertical duct through which passes the stem 25 of the puppet valve 26 that controls the communication of the recess 24 with said control chamber. Similarly the communication of the upper recess with 90 said control chamber is controlled by rod 32 the lower end of which has a conical form to serve as a valve. The stem 25 enters a central hole in the lower end of rod 32 while the puppet valve 26 is inwardly 100 pressed up against its seat by a spring 22.

Above B² is the magnet C², which has its coils 34, on spool 31, contained in a pocket between the magnetic core 33 and the

external magnetic shell 30. The shell 30 is surrounded by a screw cap 35 and a space is left under this cap for an armature disk 36 pressed upward by a spring 37. From 5 the center of the armature disk the non-magnetic rod 32 passes down through an axial perforation in core 33 and is formed, as aforesaid, with a conical end serving as a valve. A magnet of this description can remain indefinitely on closed circuit without material heating since it means but an extremely minute current to operate and maintain it.

The magnet C², and the similar magnet 15 C¹, are controlled by a switch E, the blade 41 of which is pivoted on a plate 40 connected to one terminal of the battery or source of current. The other side of the battery circuit is branched through the respective magnets C¹ and C² and the two branches terminate at the respective contacts 42 and 43 of the switch E. The movement of blade 20 41 to the left will energize magnet C² through contact 42 and its reverse movement to the right will energize magnet C² 25 through contact 43, as shown in the drawing, while either magnet may be deenergized by moving the blade away from the corresponding contact 42 or 43 without energizing 30 the opposite magnet.

The operation is as follows: To close door D, move blade 41 to contact 43. This energizes magnet C² which draws down its armature disk 36 against the force of spring 37. The armature forces down the rod 32 which strikes the upper end of stem 25 a slight blow, knocking the puppet valve 26 off its seat against the force of spring 22, and then by a further movement closes the 35 passage from the control chamber to the recess 28 and exhaust duct 27. Thereupon air flows from supply pipe 13, through branch 14, recess 24, control chamber 23 to the rear end of cylinder 2 which then acts 40 to drive crossheads 5 and 6 together with door D to the right to close it. The door can be instantly stopped at any point in its course by moving blade 41 away from contact 43 and so can be advanced to its closing 45 position step by step, or it may be left at any point with both cylinders exhausted and the pressure on the piston thereby equalized, so that the door will be left free to be worked by hand. The movement of blade 41 to the 50 left will similarly cause magnet C¹ to admit air pressure to the rear of cylinder 1 to operate the door from right to left to open it. Obviously, the air pressure will remain on the motor cylinder so long as the door is 55 in an extreme position, either opened or closed, thereby avoiding the need of latches or locks and at the same time the circuit will remain closed through one magnet or 60 the other. It may be added that this closed 65 circuit condition is made practicable by the

special construction of the magnetic valve as above described, the magnet of which requires but an infinitesimal amount of current to operate it and maintain it after operation.

What I claim as new and desire to secure by Letters Patent is:

1. A double-acting fluid pressure door operating device comprising a motor, a source of fluid pressure having branches 70 communicating with each end of the motor, a magnetic valve controlling each branch and provided with an exhaust, and an electric circuit including the valves and a controlling switch having separate contacts connected with the respective valves, and an independent contact connected with both valves whereby one valve may be open to exhaust and the other valve closed to exhaust but open to admit pressure to the 80 motor, or the circuit opened to place both valves in position to exhaust.

2. A double acting fluid pressure door operating device comprising a motor, a source of pressure supply connected to each end of 90 the motor, separate valves controlling the admission of pressure to the ends of the motor and provided with exhausts, and an electric circuit including the valves and a controlling switch having separate contacts connected with the respective valves, and an independent contact connected with both 95 valves whereby one valve may be open to admit pressure to one end of the motor and the other valve open to exhaust, or both 100 valves open to exhaust.

3. A double acting door motor comprising a fluid pressure motor, separate means controlling the admission of pressure to each end thereof and provided with pressure exhausts, and an electric circuit including said controlling means, and a switch having separate contacts connected with the respective valves, and an independent contact connected with both valves whereby the pressure may be independently admitted to either end of the motor, or the controlling means placed at the exhaust to prevent pressure being admitted to the motor.

4. In a double acting door operating device, the combination with a fluid pressure motor, a source of pressure supply for each end thereof, separate valves controlling the admission of pressure to the ends of the motor, and provided with exhausts, and an electric circuit including the valves and a controlling switch having separate contacts connected with the respective valves, and an independent contact connected with both valves whereby one valve may be open 110 to admit pressure to the motor and the other valve open to exhaust, or both valves open 115 to exhaust.

5. In a double acting door operating device, the combination with a fluid pressure 120

motor, and a source of pressure supply for each end thereof, of a separate valve for controlling the admission of pressure to each end of the motor and for exhausting the pressure, and an electric circuit including the valves and a controlling switch having separate contacts connected with the respective valves, and an independent contact connected with both valves whereby one valve 10 may be opened to admit pressure to the

motor and the other opened to exhaust, or 15 both valves opened to exhaust to permit manual operation of the doors.

In witness whereof I have hereunto set my hand, before two subscribing witnesses, this 25th day of May, 1912.

THOMAS FARMER, JR.
